ABSTRACT

A cloth roll take up for a textile loom, having means for guiding the cloth from the delivery roll and thence beneath the loom, includes a pair of transversely spaced vertical frame members each including a pair of longitudinally spaced standards carried outboard of the loom frame members adjacent the rear of the loom for positioning a pair of spaced horizontal transverse frictional take up rolls with means for driving the rolls for building a cloth roll above the loom, the cloth being guided from beneath the loom substantially vertically behind the loom warp beam.

Fig. 2.**Fig. 1.**

LOOM CLOTH ROLL TAKE UP

This invention relates to an improved cloth roll take up for a loom wherein a pair of transversely spaced members are carried outboard of the loom frame members adjacent the rear of the loom for carrying driven roll supports above the loom for receiving cloth from beneath the loom behind the loom beam. Such an arrangement permits the building of a very large cloth roll without interference with the various loom parts while saving space in the mill to accommodate personnel and auxiliary equipment.

BACKGROUND OF THE INVENTION

Loom cloth roll take ups have been proposed wherein surface driven take up rolls are carried on the top of the loom and mounted on the loom frame. Such structure is shown in British Pat. No. 1,018,409, published Jan. 28, 1966 and similar structure is shown in U.S. Pat. Nos. 2,811,176, 3,502,115 and 3,677,305. The prior art also contemplates a winding mechanism comprising a pair of spaced horizontal transverse frictional take up rolls which are suitably driven and mounted forwardly of the loom, such as illustrated in U.S. Pat. No. 3,433,430, but space requirements are increased thereby. It has heretofore proved to be impractical however in practice to position frictional take up rolls over the loom for building very large rolls while conserving space within the mill. It has been found that exceptional vibration is imparted from the loom frames to the take up mechanism carried thereby. Moreover, in the case of very large rolls it is necessary that the take up mechanism be cantilevered outwardly behind the loom to avoid interference of the cloth with the loom beam.

It is important to overcome the vibration problem and provide a practical structural arrangement for supporting the take up equipment plus the very large cloth roll while avoiding obstructing the working mechanism of the loom. It is also important to provide effective mechanisms for exerting control over the cloth for building a tight very large cloth roll while disposed out of the way of the loom parts, as well as personnel and auxiliary roll doffing equipment such as lift trucks, etc.

SUMMARY OF THE INVENTION

It has been found that by positioning spaced vertical frame members, each including a pair of longitudinal standards, outboard of the frame members of the loom, it is possible to avoid excessive vibration and provide sufficient support to carry the required load in a position to avoid interference by the cloth with the loom beam. Since the frame members are constructed of spaced standards, reasonable access may be had for operating and maintaining the various conventional loom parts with which the device is used. It has further been found that a take up mechanism having a pair of driven spaced horizontal transverse frictional take up rolls with means for guiding the cloth thereto, including a transverse roll carried in horizontal alignment with an adjacent take up roll, affords effective control upon the cloth by maintaining a predetermined wrap of the cloth about the adjacent take up roll.

An imperforate dirt shield is carried by the loom in superposed relation to a rim of cloth passing beneath the loom. The driving means preferably includes a reversible motor driving one of the take up rolls at a first speed, a driving connection between the rolls causing

the one roll to impart rotation at a slightly different second speed to the other roll for building a tight cloth roll, and means releasing such driving connection when the motor is reversed to permit an even take off of cloth avoiding any tendency to pucker

By positioning the vertical frame members outboard of the loom frame members a sufficiently rugged structure can be afforded to carry the various drive mechanisms for the frictional rolls above the loom while isolating the drive and take up mechanism from the oscillations and vibrations during weaving. Horizontal alignment of the peripheries of the transverse roll and take up roll facilitates a manual placement of a full cloth roll thereon making it more accessible to the tines of a lift truck for doffing.

BRIEF DESCRIPTION OF THE DRAWING

The construction designed to carry out the invention will be hereinafter described, together with other features thereof.

The invention will be more readily understood from a reading of the following specification and by reference to the accompanying drawing forming a part thereof, wherein an example of the invention is shown and wherein:

FIG. 1 is a perspective view illustrating loom equipment with a cloth roll take up constructed in accordance with the present invention including the drive mechanism and control devices for handling the cloth,

FIG. 2 is a longitudinal sectional elevation taken on the line 2-2 in FIG. 1 further illustrating the support structure and frictional rolls, and

FIG. 3 is a side elevation looking toward the right hand side of FIG. 1 showing a take up drive.

DESCRIPTION OF A PREFERRED EMBODIMENT

The drawing illustrates a cloth roll take up for a loom having a loom beam adjacent the rear of the loom and a cloth delivery roll mounted to receive woven cloth carried between the loom side frame members adjacent the front of the loom. The take up has means for guiding the cloth from the delivery roll and thence beneath toward the rear of the loom.

A pair of transversely spaced vertical frame members A, each including a pair of longitudinally spaced standards, are carried outboard of the loom frame members adjacent the rear of the loom. A mounting platform B is carried adjacent the top of the frame members. A pair of spaced horizontal transverse friction take up rolls C are carried for rotation by a pair of spaced roll supports D. The roll supports are carried by the platform in transverse alignment therewith for supporting the pair of take up rolls for rotation above and in substantial vertical alignment with the loom beam. Means E for driving the pair of take up rolls are carried by the platform. Means F are provided for guiding the cloth from beneath the loom substantially vertically behind the loom beam to the take up rolls. Preferably, the means F for guiding the cloth from beneath the loom includes a transverse roll carried in horizontal alignment with an adjacent take up roll C for affording a predetermined wrap of the cloth thereabout.

A loom of standard construction is broadly designated at 10 and includes a pair of side frame members 11 and 12 bridged by the usual breast beam 13. A loom warp beam 14 is carried adjacent the rear of the frame members 11 and 12 and supplies warp yarn 15 over the

usual whip roll 16. The warp yarn 15 forms a shed 16a for making the cloth 17 which is illustrated as passing over the breast beam 13 to the usual delivery or take up sand roll 18. At this point the procedure varies from the conventional and the cloth is carried over a press roll 19 and thence downwardly around a pair of guide rolls 10 and 21 beneath the loom preparatory to its being guided by the mechanism hereof and wound into a very large cloth roll.

A pair of transversely spaced vertical frame members A, each including a pair of longitudinally spaced standards 22 are braced at the bottom by cross frame members 23 and at the top by the various components of the mounting platform B which bridge the respective standards 22 and extends transversely between the respective vertical frame members A.

The platform B on the left hand side of FIG. 1 includes spaced horizontal transverse members 24 which are bridged by a suitable longitudinal frame member 25. The frame A on the right hand side of FIG. 1 is bridged by a longitudinal member 26. The platform further includes a transverse frame member 27 which bridges the longitudinal frame members 25 and 26 to provide rigidity to the platform structure as well as the frame members which support it. Suitable angularly disposed frame members 28 may be employed as desired to add rigidity to the aforesaid frame and platform structure. An additional transverse member 29 (FIG. 2) spans the vertical frame members and carries a pair of spaced standards 30 for limiting transverse movement of the cloth roll upon the frictional take up rolls C. The transverse frame member 29 is secured to the frame and platform members through a pair of spaced roll supports D.

The means E for driving the pair of take up rolls C are carried by the platform and contained within a suitable housing 31. The means E includes a motor 32 which through a gear box 33 drives a chain 34 for imparting rotation to the frictional take up rolls C through a sprocket 35. The sprocket 35 is carried by the forward roll 36 of the rolls C. The back roll 37 is driven through a sprocket 38 which in turn is driven through an endless chain 39 driven by the sprocket 40 carried by the opposite end of the roll 36.

A means F for guiding the cloth beneath the loom includes a guide roll 41 carried by extensions 42 of the frame members 11 and 12 and is positioned to guide the cloth upwardly substantially vertically behind the loom beam to a cooperating transverse roll 43 which controls the wrap of the cloth 17 and the adjacent frictional roll 37. Thus, the tension exerted upon the cloth 17 as it is wound about a suitable core 44 to form a cloth roll 17a, is continuously built upon the frictional rolls C to a very large size.

An imperforate dirt shield 17b is carried by brackets 17c by the loom side frame members just above the run of cloth passing beneath the loom. The motor 32 is preferably a reversible motor for backing cloth off the cloth roll producing slack in the vertical run of cloth past the loom beam. Thus, access may be had as when a warp end comes down. It has been found desirable, in order to get a tight wrap on cloth on the cloth roll, to drive one of the take up rolls at a slightly faster speed than the other. In the embodiment illustrated the take up roll 36 is driven faster, having one less tooth than take up roll 37. As noted in FIG. 3 a ratchet wheel 45 is keyed to the shaft carrying roll 37 as at 45a. A spring

biased pawl 46 is pivoted as at 46a upon the sprocket. During reversing the pawl will be out of engagement with the ratchet so that the rolls 37 and 36 will be driven at the same speed as has been found necessary to avoid placing a pucker in the cloth roll on reversing.

While a preferred embodiment of the invention has been described using specific terms, such description is for illustrative purposes only, and it is to be understood that changes and variations may be made without departing from the spirit or scope of the following claims.

What is claimed is:

1. In a cloth roll take up for a loom having a loom warp beam adjacent the rear of the loom and a cloth delivery roll mounted to receive woven cloth carried between loom side frame members adjacent the front of the loom, said take up having means for guiding the cloth from said delivery roll and thence beneath toward the rear of the loom, the improvement comprising:

- A. a pair of transversely spaced vertical frame members, each including a pair of longitudinally spaced standards, carried laterally outboard independently of said loom frame members adjacent the rear of the loom;
- B. a mounting platform carried by said frame members above the loom;
- C. a pair of spaced horizontal transverse friction take up rolls;
- D. a pair of spaced roll supports carried by said platform in transverse alignment therewith for supporting said pair of take up rolls for rotation above and in substantial vertical alignment with said loom beam;
- E. means for driving said pair of take up rolls carried by said platform; and
- F. means for guiding the cloth from beneath the loom substantially vertically behind the loom warp beam to the take up rolls.

2. The structure set forth in claim 1, wherein said means for guiding the cloth from beneath the loom includes a transverse roll carried in horizontal alignment with an adjacent take up roll for affording a predetermined wrap of the cloth about said adjacent take up roll.

3. The structure set forth in claim 1, including an imperforate shield carried in superposed relation to cloth passing beneath the loom.

4. In a cloth roll take up for a loom having a loom warp beam adjacent the rear of the loom and a cloth delivery roll mounted to receive woven cloth carried between loom side frame members adjacent the front of the loom, said take up having means for guiding the cloth from said delivery roll and thence beneath toward the rear of the loom, the improvement comprising:

- A. a pair of spaced horizontal friction take up rolls for face driving a cloth roll;
- B. means for mounting said take up rolls above the loom laterally outboard and independently of the loom;
- C. means for driving said pair of take up rolls, said means for driving including;
- D. a reversible motor driving one of said take up rolls at a first speed;
- E. a driving connection between said rolls causing said one roll to impart rotation at a slightly different second speed to the other take up roll for building a tight cloth roll; and

F. means releasing said driving connection when said motor is reversed; whereby cloth may be evenly taken off the roll avoiding any tendency to pucker.

5. The structure set forth in claim 4, including a transverse roll carried in horizontal alignment with an adjacent take up roll wherein a portion of the peripheries of said rolls are aligned for supporting the cloth roll for removal from the loom.

6. In a cloth roll take up for a loom having a loom warp beam adjacent the rear of the loom and a cloth delivery roll mounted to receive woven cloth carried between loom side frame members adjacent the front of the loom, said take up having means for guiding the cloth from said delivery roll and thence beneath toward the rear of the loom, the improvement comprising:

A. a pair of spaced vertical frame members carried laterally outboard and independently of said loom

frame members;

B. a mounting platform carried by said frame members above the loom;

C. a pair of spaced horizontal friction take up rolls;

D. a pair of spaced roll supports carried by said platform in alignment therewith for supporting said pair of take up rolls for rotation above said loom;

E. means for driving said pair of take up rolls carried by said platform; and

F. means for guiding the cloth from beneath the loom to the take up rolls.

7. The structure set forth in claim 6, wherein said means for guiding the cloth from beneath the loom includes a roll carried in horizontal alignment with an adjacent take up roll for affording a predetermined wrap of the cloth about said adjacent take up roll.
